[57] CLAIM

The ornamental design for a bicycle pedal, as shown
and described.

DESCRIPTION

FIG. 1 is a front elevational view of the bicycle pedal
showing our new design;

FIG. 2 is a right-side elevational view thereof;

FIG. 3 is a left-side elevational view thereof;

FIG. 4 is a rear elevational view thereof;

FIG. 5 is a top plan view thereof;

FIG. 6 is a bottom plan view thereof;

FIG. 7 is a right side elevational view shown partially in
section along the line VII—VII in FIG. 5 illustrating
the spherical concavity of the upper surface thereof;
and,

FIG. 8 is a front elevational view shown partially in
section along the line VIII—VIII in FIG. 5 further
illustrating the spherical concavity of the upper surface
thereof.

The strap has been omitted in FIGS. 7 and 8 for convenience
of illustration.
